CLAIM

The ornamental design for hose-attached pressure spray washer or the like, as substantially shown and described.

DESCRIPTION

FIG. 1 is a right front perspective view of a hose attached pressure spray washer or the like showing our new design;

FIG. 2 is a left front perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and

FIG. 8 is an exploded perspective view thereof, showing the wand in an open condition.

FIG. 1

FIG. 2

FIG. 3

FIG. 4

FIG. 6

FIG. 5

FIG. 7

FIG. 8
